The Schedule referred to in the letter Patent am making part
of the same containing a description in the words of the his Christian
Sheaffer himself of his improvement for the machine for making
Cider. - To all to whom these powers shall come, - But it is known
that A. Christian Sheaffer of the Township of Lebanon, in the
County of Lebanon and State of Pennsylvania have invented a new
(and very useful) improvement in the machine for making cider
usually called, Cider-press, the following being a full and exact description
of the construction and operation of the said machine as invented, or
improved, by me. The machine consists of two pair of staves, a former, an
apple mill made of three cog-wheels, cager or receiver, a press beam, the main
beam, one assistant beam (without) the weight-beams &c. A is the press
beam. It is a pair of staves of which there are two, viz one to correspond with
each of the sides of the press beam. C is a hopper or rightangled box wherein
the apples are stored of which there are two, viz one. The other side of the
mill (and placed at the contrary corner) is a pair of the staves and one of the
hoppers or rightangled boxes as shown in the drawing accompanying this
specification (Fig 11). D is the mill and consists as before said of three cog
wheels, part of the one (and the whole of another of which are shown in the
drawing, Fig 11, being hid by the hopper or rightangled box C - E is one
of the main beams of which there are two, viz one to correspond with it
on the other side of the press beam. F is a Spout or Conduiter. It is a
thin and light piece of timber which is to be inserted in the hole of the beam E, it is to be
made of timber, one piece on each side of the press beam and one on
top (at each end) the side pieces extend the the beam and fasten
at the bottom. G is an assistant beam. H is a piece of plank which has
a hole fitted to the beam and may be called a nut, to correspond to
the assistant beam; it is made from by, two strong wires or bay of iron
as shown in the drawing. I, 2 & 4 are keys to regulate the mill. In case of
friction L is a piece of timber with two end pieces attached to it, at
each of which a hook is attached as M is another piece of timber.

with one piece, it is at right angles with the other and connects with it. The one piece attached to the main timber, are not quite as long as those before named, and are intended for the guiding of the horses' heads. The frame pieces A. B. C. D. have each of them one to correspond with it, on the other side of the press beam. The machinery in different parts is strengthened with iron to prevent disorder in case of friction, even so, I omitted to say that one of the main screws is seen in the drawing Fig. II. that there are two spurs or conducting licks, viz one on the other side of the mill seen in the drawing Fig. II. and facing the main door on that side, and under the hopper or right angled top, in fact - also omitted to say that the Wright box or the stairs always rests on the ground. The operation is as follows. The apples are carried up the stairs on either side, thrown into with of the hoppers or right angled tops, on either side of the press beam, the horses are then driven round which sets the mill going and drives the apples, the apples then tumble into the cage or receiver, then the cage or receiver is above one eighth part of mashed apples, a layer of straw must then be put in, and so alternately until the cage or receiver is full. The cage or receiver which is in fact, is then put on a beam ^{the top of} which stands on each side on the platform of the stairs and the other end on the cage, this is done on both sides of the machinery. One man stands on one of them and another man stands on the other, they stand by, holding of short poles, lighter the main screws, which as before hinted, pass the timber C. and rest with their ends on the top of the cage or receiver, next along poles are put into the holes of the main screws, and screws are turned by means of the top part of the machinery in that part to which the horses belong, but finally the main screws will carry the press beam and the Wright box, near the assistant beam to side, to prevent the much weight to rest on the main screws, the assistant beam is turned, which then hangs part of the machinery. The going along poles will cause the juice of the apples, or the cider to run on the top of the cage or receiver which is so constructed, as to drive the cider down into a tank or something else at O. The machinery described by me

1455

may be variously modified, and arranged, whilst the same general principles or modes of action as those upon which my improvement are dependent may be substantially retained, in claiming certain things as my invention therefore it is to be understood that I do not intend to limit myself to the precise modes and forms by me set forth, but to vary the same in any way I may deem proper, whilst the same results are attained by analogous means. I claim as my invention the whole of the machinery, excepting what I have named the cage, or receiver, the bed or base belonging to the cage or receiver, and the manner of mixing the flour with the ground apples, or mashing the mashed apples.
